Patented Aug. 29, 1922.

FIG. 1

Joseph Carl Timberlake,
INVENTOR

BY *Fetherstonhaugh & Co*

ATTORNEY

FIG. 2

UNITED STATES PATENT OFFICE.

JOSEPH CARL TIMBERLAKE, OF WHEELING, WEST VIRGINIA.

MACHINE FOR SEPARATING STICKERS ON THE OPENING FLOORS OF TIN MILLS.

1,427,177.

Specification of Letters Patent. Patented Aug. 29, 1922.

Application filed January 24, 1921. Serial No. 439,640.

To all whom it may concern:

Be it known that I, JOSEPH CARL TIMBERLAKE, a citizen of the United States, residing at 822 Market Street, in the city of 5 Wheeling, in the county of Ohio and State of West Virginia, have invented certain new and useful Improvements in Machines for Separating Stickers on the Opening Floors of Tin Mills, of which the following is a 10 specification.

My invention relates to improvements in machines for separating sheet metal plates or stickers as they are called and the object of the invention is to device a machine whereby the plates or stickers, which adhere after being rolled and cut, may be separated without difficulty and without liability of spoiling the sheet.

A further object is to dispose with all 20 troublesome handwork and the waste incident to such work.

My invention consists of a pair of rolls journalled in suitable bearings, suitably driven, a pair of flaring guides suitably supported in the frame and extending towards the tangential point of the rolls, and beaters located between the flaring guides suitably driven, and designed to operate on the adhering plates as they are pulled through the 30 rolls.

Fig. 1 is a perspective view showing my machine for separating the plates or stickers.

Fig. 2 is a view of portions of the rolls, the guides, and the beaters, showing the 35 plates or stickers being separated.

In the drawing like characters of reference indicate corresponding parts.

1 and 2 are the rolls of my machine which are journalled in suitable bearings in the 40 bearing frames 3 and 4.

The rolls are shown driven through gearing from the electric motor 5.

6 and 7 are flaring guides suitably held in the frames 3 and 4.

45 8 and 9 are spindles journalled in suitable bearings in the frames 3 and 4. The spindle 9 is driven by an electric motor 10 and communicates motion by means of the pinions 11 and 12 to the spindle 8.

50 13 and 14 are beaters located respectively on the spindles 8 and 9.

15 and 16 are the sheet metal plates which are designed to be separated. The plates are drawn through the rolls by the pressure 55 of the rolls on them and in the direction in-

dicated by arrow and are separated by the beaters 13 and 14.

Previous to my invention it has been difficult to separate the sheets or stickers after they have passed through the hot rolls and 60 have been folded and cut by shears into sheets. The cause of the adhering of the sheets together it is not necessary here to account for, but it is well known that previous to my invention laborers had great 65 difficulty in separating these sheets by hand with hatchets or sharp instruments. Often in their efforts to separate the sheets they would knock a hole in them and thus spoil the sheet. In their case it would be possible 70 to separate the sheets for a certain distance but no further and thus the sheets would have to be scrapped.

It will be understood that the beginning of the separation has still to be made by 75 the laborer but he has only to separate a corner or just enough so that the beaters can be placed between the sheets and the corners or edges caught under the rolls when the plates or sheets can be pulled 80 through by the pressure of the rolls and separated by the beaters.

It will be seen from this description that I provide a very simple device saving time and labor and at the same time insuring 85 the effectual separation of the plates or sheets with a minimum loss of time and material.

What I claim as my invention is:

1. In a sheet separating apparatus, the 90 combination with sheet pulling rolls of revolving beaters arranged to operate between the sheets to separate the same.

2. In a sheet separating apparatus, the combination with sheet pulling rolls, of 95 revolving beaters arranged to operate between sheets of a pack to separate the same, and guides between which the beaters are positioned.

3. In a sheet separating apparatus, the 100 combination with sheet pulling rolls spaced apart to afford a passage between them of revolving beaters located on opposite sides of the plane of the passage and designed for interposition between partially separate 105 sheets of a pack to complete the separation of the sheets as they are drawn between the rolls.

4. An apparatus as recited in claim 3, including guide members between which the 110

beaters are positioned, said guides being inclined with respect to both the beaters and the rolls.

5. A sheet separating apparatus comprising frame members, pulling rollers extending between said frame members and supported thereby, said rolls being spaced apart to afford a passage between them, revolving shafts extending between said frame members at one side of said rolls and approximately opposite said passage, beaters car-

ried by said shafts for interposition between partially separated sheets of a pack to complete the separation of the sheets as they are drawn between the rolls, and guides, between which the beaters are positioned, extending between said frame members and supported thereby. 15

In testimony whereof I affix my signature.

JOSEPH CARL TIMBERLAKE.
